(57) **CLAIM**

The ornamental design for a portion of a lighting fixture, as shown and described.

DESCRIPTION

This application is related to concurrently filed U.S. design patent application Ser. No. 29/264,458, entitled Lighting Ornament and U.S. design patent application Ser. No. 29/264,472, entitled Lighting Fixture, the subject matter of which are incorporated herein in their entirety by reference.

FIG. 1 is a perspective view of a portion of the lighting fixture in accordance with the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom view thereof;

FIG. 7 is a perspective view of the portion of the lighting fixture of FIG. 1 shown configured in a chandelier in dashed lines having one tier of arms; and,

FIG. 8 is a perspective view of the portion of the lighting fixture of FIG. 1 shown configured in a chandelier in dashed lines having two tiers of arms.

The broken lines in the figures are for illustration purposes only and form no part of the claimed invention.

1 Claim, 8 Drawing Sheets
